UNITED STATES PATENT OFFICE.

JOSEPH J. HILEMON, OF CHICAGO, ILLINOIS.

HOSE-SUPPORTER.

1,333,417.

Specification of Letters Patent. Patented Mar. 9, 1920.

Application filed March 9, 1917. Serial No. 153,647.

To all whom it may concern:

Be it known that I, JOSEPH J. HILEMON, a citizen of the United States, residing at Chicago, in the county of Cook and State of Illinois, have invented certain useful Improvements in Hose-Supporters, of which the following is a specification, reference being had therein to the accompanying drawing.

10 The present invention has reference generally to improvements in that class of inventions known as garment supporters and more particularly relates to a hose supporter.

As the primary aim and object this invention contemplates the provision of a novel hose supporter embodying novel engaging means adapted for attachment on a portion of a nether garment and on a portion of the hose without encircling the limb of the 20 wearer for supporting the hose, thereby obviating the possibility of stopping the circulation of the blood as is the case in the majority of hose supporters at present in use, the device being particularly designed for 25 those persons who are unable to conveniently use a hose supporter of the limb encircling type.

More particularly, the present invention embraces the provision of an elastic connecting element interposed between the engaging means, improved flexible means being provided for connecting the engaging means to the flexible connecting element, thus providing a device of this character that is 30 practically flexible throughout and which does not interfere with the action of the wearer, being convenient and practical.

Among the other aims and objects of the present invention may be recited the provision 40 of a device of the character mentioned with a view to compactness, and in which the number of parts are few, the construction simple, and the cost of production low.

Other objects as well as the nature, characteristic features and scope of this invention will be more readily apparent from the following description taken in connection with the accompanying drawings, and pointed out in the claim forming a part of 50 this specification.

The preferred embodiment of the present invention is clearly illustrated in the accompanying drawings, in which:

Figure 1 is a front elevation of the device 55 in an operative position.

Fig. 2 is an enlarged front elevation of

the device detached illustrating the construction thereof, and

Fig. 3 is a perspective detail showing the stud engaging loop on the stud. 60

Similar characters of reference are employed in all of the above described views, to indicate corresponding parts.

Referring now, more particularly, to the accompanying drawings I provide my improved elastic means in the present instance consisting of an elastic strip 1 each end of which is folded upon itself as indicated by the numeral 2 and stitched to the main portion as indicated by the numeral 3, being 70 engaged in a metallic loop 4 preparatory to being stitched.

With a view toward providing my improved flexible attaching means for the engaging means I employ chains 5. The inner end link 6 of each chain is pivotally engaged in an ear 7 formed on the outer portion of each loop 4. The co-operative engaging means is now connected to the flexible means and consist of relatively small 80 rectangular plates 8 having the end edges rounded and having openings 9 in the inner ends for pivotally receiving the outer end links of the chains 5. Studs 10 are formed on the outer surface adjacent the outer ends 85 of the plates while heads 11 are formed on the outer ends of the studs. Elongated stud and article engaging loops 12 have their inner end surfaces enlarged and curved as indicated by the numeral 13 to facilitate 90 the passing of the heads 11 therethrough while the inner surfaces are further inclined or converged toward the outer end as indicated by the numeral 14 so that when applied as indicated in Fig. 1 the inner surfaces will be straddled about the shanks of the studs 10 beneath the heads 11 serving to 95 clamp a portion of a nether garment and a portion of a hose therein. It will be observed that the stud engaging loops are 100 practically twice as long as the plates 8 so that when the parts are in an extended position they will terminate in substantial alinement.

In applying the improved hose supporter 105 one of the plates 8 is inserted beneath the outwardly folded portion of the limb of a nether garment and is arranged practically parallel to the surface of the limb of the wearer whereupon the engaging loop is 110 moved upwardly so that the stud carrying the portion of a nether garment will pass

through the opening and by pulling the stud engaging loop 12 downwardly the nether garment will be clamped between the stud and the loop. The other plate is passed 5 between the nether garment and the upper portion of the hose while the stud engaging loop is moved downwardly so as to engage the enlarged circular inner surface thereof, which in effect is an opening about 10 the stud carrying the portion of the hose and is pulled upwardly so that the converging surfaces clamp the hose to the shank of the stud being prevented from displacement because of the head. In use it is 15 thought to be apparent that because of the elastic connecting means and the flexible means as well as the pivotally connected engaging means on the flexible means that all the parts are permitted of having free 20 movement and thereby obviate any inconvenience to the wearer. Incidentally it will be apparent that the device is especially adapted for those persons who cannot use the customary form of limb encircling hose 25 supporter on account of the same stopping the circulation of blood in the limbs.

From the foregoing description it is thought that a further detailed description of the invention is unnecessary. Likewise 30 it is believed that the advantages of the invention will be readily apparent.

It will be understood that the foregoing description and accompanying drawings comprehend only the general and preferred

embodiment of my invention and that various minor changes in detail of construction, proportion and arrangement of the parts may be made within the scope of the appended claim and without sacrificing any of the advantages of my invention. 35 40

Having thus fully described my invention, what I claim as new and desire to secure by Letters-Patent is:

In a device of the character described, an attaching loop, an ear formed integral with 45 the loop and projecting from the lower edge medially thereof, a chain embodying a plurality of links the inner of which is loosely connected to the ear, a relatively flat plate having an opening near its inner end for 50 loose connection with the outer link of the chain, a headed stud formed integral with one face of the plate near the outer end thereof, and an elongated, relatively flat, 55 stud engaging loop stamped from a piece of sheet metal and having a small opening near the inner end for loose connection with the inner link of the chain and also having its inner edge near the inner end enlarged and rounded and its inner side edges tapered toward the outer end and arranged in frictional engagement with the stud subsequent to the engagement of the stud with an article of apparel and subsequent to the disposition of the inner mounted edge of 60 65 the loop thereabout.

In testimony whereof I affix my signature.
JOSEPH J. HILEMON.
